APPARATUS FOR PHOTO-TELEPHONES
AND THE LIKE

Robert Mechau, Hugo Eisenhut, and Paul Reinsch, Jena, Germany, assignors to the firm of Carl Zeiss, Jena, Germany

Application August 11, 1934, Serial No. 739,382
In Germany August 17, 1933

6 Claims. (Cl. 88—61)

An application has been filed in Germany, August 17, 1933.

The present invention concerns an apparatus for photo-telephones and the like, in which the pencil of light for the transmission of sound is modulated by a body that moves relatively to a totally reflecting surface and is rigidly connected to an electrically influenced part. The electric influence may be for instance electromagnetic or electrostatic. The movement of the said body relative to the reflecting surface is to effect a more or less pronounced influence upon the quantity of reflected light rays. This movement is generally at right angles to the reflecting surface and covers so short distances as correspond to wave-lengths of light. These apparatus are therefore very sensitive as regards such changes in the position of the said body as are unfortunately caused by influences of temperature and the like, the consequence being the necessity of readjustments of the apparatus even when this apparatus is in operation.

According to the invention, the electrically influenced part of the apparatus, for instance the armature of the electromagnet when the influence is electromagnetic, and the body effecting the modulation of the pencil of light are placed on the body containing the totally reflecting surface, and conveniently on the said reflecting surface itself. Not only is there attained in this manner that all moving parts occupy the least possible space, as a consequence of which undesired intermediate members between the electrically influenced part and the part changing the total reflection are avoided and the influence of changing temperatures is comparatively small, but a change of position of the moving parts as a whole relative to the reflecting surface is avoided.

40 The moving body effecting the modulations of the pencil of light rests conveniently against two points of the reflecting surface which determine an axis about which the body may oscillate. In this manner there is maintained the parallelity of the optically effective surface of the moving body relative to the reflecting surface, which is of importance if the apparatus is to work correctly.

45 The optically effective surface of the moving body or the effective part of the totally reflecting surface is conveniently provided with flutes, flutes having proved to prevent an undesired adhesion of the moving body to the reflecting surface.

50 The accompanying drawing illustrates a constructional example of an apparatus according to

the invention. Figure 1 shows schematically a top of view of the optical system of the apparatus. Figures 2 and 3 represent the apparatus in a horizontal and a vertical partial section, respectively. Figures 4, 5 and 6 illustrate views of single parts, Figure 5 being reproduced on an enlarged scale.

5 The optical system of the apparatus consists of a condenser *a*, which converges the rays of a source of light *b*, a rectangular prism *c* and an objective *d*. A glass plate *e* lies against, and is displaceable at right angles to, the surface *c*¹ of the prism *c*. That surface of the glass plate *e* which faces the prism *c* is roughened by flutes *e*¹ (Figure 5). As is shown by Figures 2 and 3, 10 the plate *e* is mounted in a plate *f* of larger dimensions. This plate *f* is of iron, and the plate *e* protrudes therefrom to a slight extent. That surface of the plate *f* which faces the prism *c* has two parts *f*¹ and *f*² that protrude from the said 15 surface. These two parts, by means of which the plate *f* lies against the prism *c*, determine an axis of oscillation *X—X* (Figure 4) of the plate *f*. By means of three cuttings *f*³, *f*⁴ and *f*⁵, the plate *f* is provided with an elastic blade *g*. Above the 20 prism *c* and the plate *f* is a piece *h* in which is disposed an adjusting screw *h*¹ that presses against the blade *g*. An elastic arm *i* which is adjustable about a bolt *i*¹ by means of a two-armed lever *j* adjustable about a bolt *j*¹ presses 25 against the plate *f* near the axis of oscillation of this plate. The arm *i* and the screw *h*¹ adjust the desired magnitude of the distance of the glass plate *e* from the surface *c*¹ or the pressure of the plate *e* against the said surface by changing 30 through the agency of the lever *j* the distance of the place at which the arm *i* lies against the plate *f* from the axis *X—X*. At the prism side of the plate *f* are provided magnets *k*. The plate *f* thus represents the armature of these magnets and 35 substitutes the diaphragm which has been in use so far and which has been mounted independently of the prism *c*.

40 Instead of roughening by flutes the surface of the plate *a*, a corresponding part of the surface *c*¹ of the prism *c* can be roughened for instance by flutes *c*² (Figure 6). There can be roughened as well both the plate *e* and the surface *c*¹.

45 When a current modulated by the human voice is made to flow through the magnets *k*, the plate *f* and the glass body *e* oscillate about the axis *X—X*, and the pressure with which the body *e* lies against the surface *c*¹ of the prism *c* is intensified or weakened accordingly. According 50

to the oscillations of the body *e*, the light emanating from the source of light *b* and striking the surface *c* is reflected by the surface *c* more or less on account of the change of the capacity of reflection of the surface *c* at the place at which this surface is in contact with the glass body *e*, the said change of capacity being due to the change of pressure, and the pencil of light leaving the objective *d* is modulated in the rhythm 10 of the current in the magnet *k*.

We claim:

1. An apparatus for photo-telephones and the like, for modulating changes of an electric current to changes of a pencil of light, having a 15 transparent body provided with a reflecting surface, this body being so disposed that the said pencil of light traverses the said body and strikes the reflecting body at an angle causing total reflection, a member provided near, and movable 20 transversely to, the said body and adapted to change the magnitude of reflection of this surface for the pencil of light by moving and touching the reflecting surface in that part at which the pencil of light strikes the surface, an electric 25 device influenced by the changes of the electric current and influencing the position of the said member, this member being movably mounted direct on the body having the reflecting surface.
2. An apparatus for photo-telephones and the like, for modulating changes of an electric current to changes of a pencil of light, having a 30 transparent body provided with a reflecting surface, this body being so disposed that the said pencil of light traverses the said body and strikes the reflecting body at an angle causing total reflection, a member provided near, and movable 35 transversely to, the said body and adapted to change the magnitude of reflection of this surface for the pencil of light by moving and touching the reflecting surface in that part at which the pencil of light strikes the surface, an electric 40 device influenced by the changes of the electric current and influencing the position of the said member, this member being movably mounted direct on the body having the reflecting surface, those surfaces of the said transparent body and the said member which face each other being provided with flutes.
3. An apparatus for photo-telephones and the like, for modulating changes of an electric current to changes of a pencil of light, having a 45 transparent body provided with a reflecting surface, this body being so disposed that the said pencil of light traverses the said body and strikes the reflecting body at an angle causing total reflection, a member provided near, and movable 50 transversely to, the said body, an electric device influenced by the changes of the electric current, the said member consisting of two parts, the one of these parts being adapted to change 55 the magnitude of reflection of the reflecting surface for the pencil of light in that part at which the pencil of light strikes the reflecting surface, the other part being influenced by the said elec-

tric part and movably mounted on the reflecting surface of the said transparent body.

4. An apparatus for photo-telephones and the like, for modulating changes of an electric current to changes of a pencil of light, having a 5 transparent body provided with a reflecting surface, this body being so disposed that the said pencil of light traverses the said body and strikes the reflecting body at an angle causing total reflection, a member provided near, and movable 10 transversely to, the said body and adapted to change the magnitude of reflection of this surface for the pencil of light by moving and touching the reflecting surface in that part at which the pencil of light strikes the surface, an electric 15 device influenced by the changes of the electric current, the said member lying at two points on the reflecting surface of the transparent body and being oscillated by the said electric device, the two said points determining an 20 axis of oscillation of the member.

5. An apparatus for photo-telephones and the like, for modulating changes of an electric current to changes of a pencil of light, having a 25 transparent body provided with a reflecting surface, this body being so disposed that the said pencil of light traverses the said body and strikes the reflecting body at an angle causing total reflection, a member provided near, and movable 30 transversely to, the said body and adapted to change the magnitude of reflection of this surface for the pencil of light by moving and touching the reflecting surface in that part at which the pencil of light strikes the surface, an electric 35 device influenced by the changes of the electric current and influencing the position of the said member, this member being movably mounted direct on the body having the reflecting surface, those surfaces of the said transparent body and the said member which face each other being 40 provided with flutes.

6. An apparatus for photo-telephones and the like, for modulating changes of an electric current to changes of a pencil of light, having a 45 transparent body provided with a reflecting surface, this body being so disposed that the said pencil of light traverses the said body and strikes the reflecting body at an angle causing total reflection, a member provided near, and movable 50 transversely to, the said body and adapted to change the magnitude of reflection of this surface for the pencil of light by moving and touching the reflecting surface in that part at which the pencil of light strikes the surface, an electric 55 device influenced by the changes of the electric current and influencing the position of the said member, this member being movably mounted direct on the body having the reflecting surface, that superficial part of the said member which is made to touch the transparent body being 60 provided with flutes.
